UNITED STATES PATENT OFFICE

137,618

DESIGN FOR A FUSE CAP FASTENER

Fritz Hermann Rolfes, Johannesburg, Transvaal,
Union of South Africa

Application June 29, 1943, Serial No. 110,566. In
the Union of South Africa March 17, 1943

Term of patent 14 years

(Cl. D30—1)

To all whom it may concern:

Be it known that I, Fritz Hermann Rolfes, a British subject, residing at Johannesburg, in the Province of Transvaal, Union of South Africa, have invented a new, original, and ornamental Design for a Fuse Cap Fastener, of which the following is a specification, reference being had to the accompanying drawing, forming part thereof.

The figure is a perspective view of a fuse cap fastener, showing my new design.

I claim:

The ornamental design for a fuse cap fastener, as shown.

FRITZ HERMANN ROLFES.
